UNITED STATES PATENT OFFICE.

PAUL HANSMANN, OF LONG PRAIRIE, MINNESOTA.

AUTOMATIC COUPLING.

1,298,698.

Specification of Letters Patent.

Patented Apr. 1, 1919.

Application filed April 23, 1917. Serial No. 163,892.

To all whom it may concern:

Be it known that I, PAUL HANSMANN, a citizen of the United States, residing at Long Prairie, in the county of Todd and State of Minnesota, have invented certain new and useful Improvements in Automatic Couplings, of which the following is a specification.

My invention relates to improvements in draft connections for coupling one vehicle behind another, as binders, wherein the succeeding vehicles are held in relatively offset positions. The object of my invention is particularly to provide a coupling connection which will automatically control the travel of one vehicle from the next forward vehicle and particularly cause each succeeding vehicle to turn a square corner.

To this end my invention consists in the construction, combination and arrangement of parts hereinafter particularly described and claimed.

In the accompanying drawings forming a part of this specification,

Figure 1 is a plan view of my improved coupling mechanism in use as a binder connection;

Fig. 2 is a perspective view of an extension member forming part of the invention;

Fig. 3 is a section taken alongside of a supporting roller, or caster, forming part of the invention;

Figs. 4 and 5 are diagrammatic views illustrating a plurality of binder frames connected together by my invention, showing by full lines, dotted lines and by dash lines the different positions of connected binder frames;

Fig. 6 is a diagrammatic view of two binder frames connected by my invention illustrating their position in turning a corner;

Fig. 7 is a similar view after the corner is turned, and

Fig. 8 is a diagrammatic view illustrating the positions the binders will assume on turning a corner without the use of my features of improvement.

Referring to the drawings A represents a frame mounted upon suitable wheels 2. In carrying out my invention I provide the fol-

lowing means for connecting together a plurality of the frames: Secured to one side of the forward frame portion 3 of the binder are brackets 4 and 5 constituting swivel supports for the cross bar 6 of the coupling mechanism hereinafter described.

A draw bar B is secured to the front of the binder in line with the bracket 5 and extends diagonally to the rear 7 of the binder to which it is secured as by staple 8. The rear end of the draw bar B extends beyond the binder frame to form a bracket projecting rearwardly from the binder frame.

Having swivel support upon the rear ends of the draw bar and the bracket 7^a is an extension frame C constructed as shown in the drawings in the form of a pair of rods 9 and 10 connected together at their rear ends by a bracket 11 to form a V-shaped frame, the front ends of the rods being bent to pass through openings 12 in the rear end of the draw bar and the bracket 7^a to form a swivel support for the frame C. The frame constituted by the rods 9 and 10 is so proportioned as to bring the rear or bracket end 11 of the frame in a position substantially in line with the center of the binder frame and at some distance at the rear thereof, with the rod 10 of the extension frame in alignment with the draw bar as shown in Fig. 1. The rear end of the extension frame carries a bracket 12^a pivotally supporting a roller or wheel 13 adapted to travel upon the ground. The link 14 extending rearwardly from the extreme rear end of the extension frame cooperates with the rear end of the bracket 11 to form a support for a cross bar 15. The connection between the link 14 and cross bar is adjustable by means of a bolt 16 adapted to pass through one of the openings 17 of the cross bar. Pivotally supported upon one end of the cross bar 15 is a rearwardly extending lever arm 18, a similar lever arm 19 being pivotally supported on the opposite end of the cross bar. The levers 18 and 19 centrally cross as shown in Fig. 1. The lever 18 at its rear end has pivotal connection 20 with one end of the cross bar 6 which cross bar has swivel connection to the front of the next binder frame. The rear end of the lever arm 19 has pivotal connection 21

with the braces 22 and 23 which project forwardly from the end of the cross bar 6 opposite to the support for the lever 18. The braces 22 and 23 thus form a forward extension of one end of the cross bar 6.

In the use of my invention where the same is applied, for instance to binders, a plurality of binders are connected together as illustrated in Fig. 1, the entire series of binders being drawn as by a tractor D. Between the tractor and the front binder coupling lever arms 18 and 19 are employed without the use of the extension frame C.

The frame C and the levers 18 and 19 are in the line of direction of the pull in the train of vehicles hitched together and in fact serve as a draw bar between adjacent vehicles.

In use, with the tractor traveling in a straight line, the coupling mechanism will hold the succeeding vehicles in offset positions as shown by full lines in Fig. 4. This is due to the fact that the straight ahead pull will hold the lever arms 18 and 19 in the position shown in Fig. 1. The amount of offset can be adjusted as by adjusting the connection between the link 14 and the cross arm 15 and between the lever 19 and the cross bar 15, which will change the relative angles of the levers. As the tractor or any one of the vehicles turns a corner the rear end of the vehicle or the rear end of the extension frame of the binder will swing in a circle. This natural swinging will turn the front end of the lever 19 forwardly with respect to the front end of the lever 18, causing the next succeeding binder to swing into the position shown in Fig. 6. Fig. 6 illustrates the position of two connected binders at the extreme corner of a turn. In this position the binders are substantially at right angles with each other. The forward binder will now travel in a straight line and as it moves forward it will exert its pull upon the pivotal connection of the front end of the lever 18, causing the levers 18 and 19 to relatively swing to bring them into the position shown in Fig. 7 and thereafter into the position shown in Fig. 1.

In the position shown in Fig. 7 the levers 18 and 19 have swung almost enough to bring the second binder into normal offset position behind the next forward binder.

I have illustrated in Figs. 4 and 5 by dotted lines and by short and long dash lines the movements of the levers 18 and 19 as the binder is swinging around a corner. The full lines of Fig. 4 indicate a tractor moving in a straight line with a plurality of binders traveling behind the same in offset positions. In Fig. 5 the full lines show the positions of the binders and engine right after the binder has turned a corner and the two succeeding binders are turning. The long dash lines of Fig. 4 illustrate the position of the lever connections and binders

when the tractor is turning the corner and the short dash lines indicate the position of the tractor and binders just as the tractor is completing a turn around the corner. In Fig. 8 I illustrate what would happen if the binders were connected together by lever arms 18 and 19 without the use of the extension frame C. As shown in Fig. 8 the binders in this case would come together and not permit the second binder to make the proper swing. In order to bring about the proper results it is necessary that the point of swinging should be about midway between the wheels and at a distance back from the binder frame equal to about one-half the distance between the wheels. This permits each succeeding binder to go up to the corner and then to swing slightly out as indicated best by dotted lines on Fig. 4 and then to turn the swing back to strike the next succeeding side of the grain at the proper angle to fully cut the corner. It has been heretofore, by the ordinarily employed adjustable connections between binders, impossible to properly cut the corners except by an operator upon each binder controlling the coupling mechanism to guide the binder around the corner. By means of the mechanism herein described I am enabled to utilize a coupling mechanism between the binders which is automatic and in which each succeeding binder is caused to turn around the corner and cut it square without the need of any operator outside of the operator for the drawing means, as the tractor.

I claim:

1. The combination with a plurality of vehicles and a coupling between said vehicles consisting of an extension projecting rearwardly from one vehicle and having two spaced pivots operative in a horizontal plane, a coupling connection journaled at one end in said pivots and located between the rear end of said extension and the next rear vehicle and pivotally connected at its other end with the latter holding said vehicles normally in relatively offset positions and causing the succeeding vehicle to be swung opposite to the front vehicle in the turning of a corner.

2. In combination with a plurality of vehicles, means connecting said vehicles and regulating the travel of one from the other, consisting of a frame pivotally supported by an extension projecting rearwardly from one vehicle, a pair of lever arms pivotally connected at their front ends to the rear of said extension, said lever arms intermediate crossing each other and having pivotal connection at their rear ends to one side of the next succeeding vehicle.

3. In combination a plurality of vehicles, means for connecting said vehicles together in relatively offset positions and controlling the travel of the rear from the forward

vehicle, consisting of an extension pivotally supported by and projecting rearwardly from one vehicle, a cross bar supported by the rear end of said extension, lever arms 5 pivotally connected to the ends of said cross bar and extending rearwardly in crossed relation, a cross bar supported by one side of the next rear vehicle and pivotal connec-

tions between the rear end of said lever arms and said second cross bar. 10

In testimony whereof I affix my signature in presence of two witnesses.

PAUL HANSMANN.
